UNITED STATES PATENT OFFICE.

BERTRAM J. GRIGSBY, OF PARK RIDGE, ILLINOIS, ASSIGNOR TO GRIGSBY-GRUNOW-HINDS CO., OF CHICAGO, ILLINOIS, A CORPORATION OF ILLINOIS.

DESIGN FOR A LENS FOR AUTOMOBILE STOP AND DIRECTION SIGNALS.

Application filed April 29, 1922. Serial No. 2,021. Term of patent 14 years.

To all whom it may concern:

Be it known that I, BERTRAM J. GRIGSBY, a citizen of the United States, residing at Park Ridge, in the county of Cook and State of Illinois, have invented a new, original, and ornamental Design for Lens for Automobile Stop and Direction Signals, of which the following is a specification, reference being had to the accompanying drawing, forming part thereof.

Fig. 1 is a face view of a lens for automobile stop and direction signals; and Fig. 2 is a bottom view of Fig. 1.

I claim:

The ornamental design for a lens for automobile stop and direction signals, as shown.

BERTRAM J. GRIGSBY.
